UNITED STATES PATENT OFFICE.

CURTIS L. LYNCH, OF CHERRYFIELD, MAINE.

CONTAINER PACK.

Application filed October 22, 1923. Serial No. 669,945.

To all whom it may concern:

Be it known that I, CURTIS L. LYNCH, a citizen of the United States, residing at Cherryfield, county of Washington, State of Maine, have invented certain new and useful Improvements in Container Packs, of which the following is a specification.

In the preservation of perishable food stuffs by sealing in closed containers, the 10 canning process is greatly simplified and certainty of preservation greatly increased if air is excluded from the pack or if present is exhausted.

While the principles of preservation in 15 vacuum or partial vacuum have been well understood and quite commonly practiced under various methods, the practice has been seriously limited by the expense so that domestic or small packs under vacuum 20 have not been possible.

It is the object of my invention to provide a simple and inexpensive pack and as a basis for such I contemplate a container or jar which may be of general standard 25 characteristics, but which will make possible practical exhaustion after filling, whereby it is possible to preserve even fresh fruits and vegetables and all without added expense or difficulty.

While capable of embodiment in somewhat varied forms and capable of use in a variety of methods and for almost all of the foods usually canned or preserved, I will without elaboration set forth only one 35 simple form as a basis of my disclosure. This illustrative embodiment however will readily suggest to those skilled in the packing art and to the manufacturers of preserving containers the other and more expensive forms which may prove justified in commercial use or more extended domestic use.

Throughout specification and drawings like reference characters are employed to designate the parts and in the drawings:

Fig. 1 is a central vertical section of a container in accordance with my invention.

Fig. 2 is an end view thereof.

Fig. 3 is a view showing the exhausting step.

Fig. 4 is a view showing the jar sealed, and

Fig. 5 is a view showing a nippled cover.

In providing a container in accordance with my invention a glass jar as 1 may be

employed. This may be of any preferred 55 type or style and may have any cover 2 and any of the various fastenings or cover retainers.

The bottom of such a jar is however recessed as at 3 and formed with a low nipple 60 vented as at 5.

At its outer end the vent 5 merges in a cup 6 adapted to hold the seal. As shown in Fig. 5 the sunken nipple 4 may be formed in the cover as at 4' and in both 65 forms the nipple is protected in its recessed position.

In connecting with the exhausting pump or system the end of a tube T can be slipped over the nipple 4 and allowed to grip under 70 the shoulder formed by the cup 6. Upon the removal of the tube T the cup 6 is sealed preferably by wax or other fusible sealing means.

Care must be taken of course in effecting 75 this sealing without loss of vacuum, especially since in the usual domestic pack the air exhaustion is never very complete, although with the usual simple pump sufficient exhaustion is had for practical purposes. 80 There is need however to conserve the partial vacuum and in order to insure this where dependence can not be placed on the dexterity of the operator, I provide preferably an initial sealing of the vent 5 by a 85 soft paraffin filling P. This may be carried up as shown in Fig. 3 to fill the cup 6. Before the exhausting tube T is slipped on the nipple this filling P is punctured to vent the contents. When the air is exhausted the 90 tube T can be pulled off with a slight lateral wiping movement of the finger which will smear over the puncture in the paraffin and prevent the inrush of air.

The cup 6 is preferably permanently 95 sealed by sealing wax which may be applied as a disc or wafer shoved into the cup and fused in place.

When so sealed the jars will stand any 100 normal amount of handling and yet may be refilled after the contents are used.

Various modifications in the form of my device may be resorted to without departing from the spirit of my invention if within the limits of the appended claims. 105

What I therefore claim and desire to secure by Letters Patent is:

1. A preserving container comprising an

enclosed vessel having one wall recessed and vanted, and a nipple within said recess and below the surface of said wall, and enclosing said vent and adapted to receive an exhaust connection.

2. A preserving container comprising a jar having a recessed bottom, a vent through said bottom, and an exterior nipple enclosing said vent and disposed within said re-

cess and below the bottom of the jar, and 10 adapted to receive an exhaust connection.

3. A preserving container having a recessed end with a vent therethrough, and a nipple enclosing said vent and disposed below the plane of the container end and 15 adapted to receive an exhaust connection.

In testimony whereof I affix my signature.

CURTIS L. LYNCH.
